UNITED STATES PATENT OFFICE.

NATHAN GUREWITSCH, OF WEIDLING, NEAR KLOSTERNEUBURG, AUSTRIA.

BUTTON-FASTENER.

1,397,376.

Specification of Letters Patent. Patented Nov. 15, 1921.

Application filed June 11, 1921. Serial No. 476,690.

To all whom it may concern:

Be it known that I, NATHAN GUREWITSCH, a citizen of Russia, and a resident of Weidling, near Klosterneuburg, Austria, have invented a new and Improved Button-Fastener, of which the following is a description.

My invention relates to button fastening means and particularly to a detachable fastener having a button head provided with a shank to be engaged by the fastener means or disengaged as may be desired.

The general object of the invention is to provide a novel fastening means that will securely hold the button in fastened position and whereby convenience is promoted in the attaching or detaching of the button.

The nature of the invention and its distinctive features and advantages will appear as the description proceeds.

Reference is to be had to the accompanying drawings forming a part of this specification, it being understood that the drawings are merely illustrative of one example of the invention.

Figure 1 is a rear perspective view of a button the back plate of the fastening device being shown separated to illustrate the parts beneath;

30 Fig. 2 is a transverse vertical section;

Fig. 3 is a perspective view of a modified form of the button head that may be employed.

In carrying out my invention in accordance with the illustrated example, the button head 10 may be of any suitable shape or design and formed with a shank 11 having an eye 12 therein. In the form shown in Figs. 1 and 2, the shank 11 is rigid whereas

40 in Fig. 3 the button head, which may be a military button, is provided with a shank 11^a connected with the head by a ball and socket connection as indicated at 13.

The fastening means comprises a front disk or plate 14 and a rear cover plate 15 therefor, between which a fastener spring is disposed as will appear. The plates 14, 15 are secured together at their peripheral edges as indicated at 16.

50 The plate 14 is formed or provided with a centrally disposed thickened portion or block 17 in which is a longitudinal slot 18 extending from the edges of the plate across the center. In association with said thickened portion 17 is a fastener spring 19

formed of a length of wire returned on itself into approximately U-form. One arm 20 of the spring lies in the slot 18 and has longitudinal movement therein to engage or disengage the eye 12 of shank 11 when said shank is projected rearwardly through a central oblong hole 14^a in the plate 14. The other arm of the fastener spring 19 has an arched portion 21 terminating at its free end in a laterally directed dog 21^a which is adapted to engage either one of two notches 22, 22^a formed in the adjacent side edge of the block 17. The spring 19 projects through an opening provided by a cut-out 14^b in the plate 14 and a corresponding cut-out 15^b in the rear cover plate 15 to be grasped between the thumb and finger for sliding the spring longitudinally. The resiliency of the spring 17 holds the dog 21^a in the notch 22 when the spring lies in the inner position with the 75 arm 20 passing through the shank 11 and in the outer position of said spring 19 the dog 21^a engages in the second notch 22^a to hold the spring against displacement. Adjacent to the rear notch 22^a a lateral protuberance 80 23 is formed on the side edge of the thickened portion 17 to limit the outward movement of the spring 19 to prevent its complete separation from the plates 14, 15.

I would state in conclusion that while the 85 illustrated example constitutes a practical embodiment of my invention, I do not limit myself strictly to the exact details herein illustrated, since manifestly the same can be considerably varied without departure from 90 the spirit of the invention as defined in the appended claims.

Having thus described my invention, I claim:

1. A fastener adapted to engage the shank 95 of a button head, said fastener comprising front and rear plates, one of which is formed with a longitudinal slot between the plates and with a pair of notches at a side of said slot, and a spring bent into approximately 100 U-shape, one arm of the spring having guided movement in said slot to be moved across the center, the front plate having a hole intersecting said slot for the protrusion of the shank of the head to bring the eye of 105 the shank into line with said spring arm, the other arm of said spring having an arched portion terminating in a laterally directed dog, said spring being accessible at the peripheries of the plates to be grasped and be- 110

ing slideable to engage or disengage the shank of a button head, and to engage its dog with either of said notches.

2. Means for fastening a button head having a shank formed with an eye, said fastening means comprising an element having a hole for the entrance of the shank, and a spring slideable in a plane approximately parallel with said element at the rear side
- 5 having a shank formed with an eye, said fastening means comprising an element having a hole for the entrance of the shank, and a spring slideable in a plane approximately parallel with said element at the rear side
- 10 thereof and having guided movement thereon, said spring being formed with a dog, and said element having a pair of notches with either one of which the spring may be engaged in its fastening position or in position
- 15 disengaged from the shank.

3. Means for fastening a button head having a shank formed with an eye, said fastening means comprising a front plate and a cover plate presenting cut-outs, a spring approximately U-shaped and movable longitudinally between said plates and accessible at said cut-outs, one of said plates having a pair of notches, and a stop protuberance adjacent to one notch, said spring having a dog adapted to engage in either of said notches, said protuberance being in line with the dog to prevent complete separation thereof from the plates. 20 25

NATHAN GUREWITSCH.
